UNITED STATES PATENT OFFICE.

JOHN GRANT, OF LOS ANGELES, AND STEWART L. CAMPBELL, OF BERKELEY, CALIFORNIA; SAID CAMPBELL ASSIGNOR TO SAID GRANT.

UNDERREAMER.

Application filed January 26, 1925. Serial No. 4,749.

To all whom it may concern:

Be it known that we, JOHN GRANT, a citizen of the United States, and resident of Los Angeles, in the county of Los Angeles, State of California, and STEWART L. CAMPBELL, a citizen of the United States, and resident of Berkeley, county of Alameda, State of California, have invented new and useful Improvements in Underreamers, of which

10 the following is a specification.

This invention relates to a rotary underreamer, such as may be used in hydraulic rotary drilling of wells. In drilling wells with rotary drilling rigs, it is the common 15 practice to introduce casing into the hole and follow the drill bit with the casing as hole is made. With the casing in position, if it is desired to ream the hole, it is necessary to have a collapsible underreamer in order that it may be introduced 20 through the casing to the lower end thereof. Such an underreamer should be automatically collapsed upon withdrawal into the casing so that it may pass therethrough. 25 Such tools must be simple in structure, durable, withstand great strain, have long life, and be easily manipulated.

These objects together with other objects and corresponding accomplishments will be 30 apparent during the course of the following description. In the accompanying drawing forming a part of this specification, an embodiment of our invention is illustrated. In the drawing:

35 Fig. 1 is an axial sectional view through my improved underreamer; Fig. 2 is an elevation of the same as seen looking in the direction of the arrows 2 of Fig. 1; Fig. 3 is a section as seen on the line 3-3 of Fig. 40 1; Fig. 4 is a fragmentary sectional view showing a roller type of cutter; and Fig. 5 is a section as seen on the line 5-5 of Fig. 4.

Referring more particularly to the drawing, the numeral 6 indicates the body or stock of the reamer, it is provided at the upper end with a tapered threaded pin 7 adapting it to be connected to a string of drill pipe. The lower end of the body has 50 a threaded tapered box indicated by 8, adapting the tool for connection to a drill bit or other tool in advance of the underreamer. Extending longitudinally of the body is a recess 9 having its inner face slant-

ing so as to form a slot open to the other 55 side of the body as indicated by 10. Extending across the recess adjacent the upper end thereof is a pivot pin 11 having an operating finger 12 mounted thereon. A pin 14 has mounted thereon a spring finger 15 60 tending to maintain the pin in its outer position. A cutter 16 is pivotally mounted upon a pin 17 within slot 10. The cutter is provided with blades 18 and 19 which are 65 diametrically opposite one another and arranged so that the cutters may be turned to dispose both blades within the boundary of the body. The cutter is provided with a notch 20 and within which the tip of finger 12 is disposed. The parts are so arranged that upon pressing finger 12 inwardly, the tip thereof will force the lug on the cutter inwardly and cause the cutter to be turned so that blades 18 and 19 are within 70 the body and in collapsed position. Pressure upon knuckle 13 to force the finger 12 inwardly will cause collapse of the cutter. Extending through the body is a water 75 passage 21 for circulation fluid, the passage being offset in the body to pass around the recess 9 and slot 10. However, the water passage may be disposed in any convenient manner.

The tool is collapsed by pressing inwardly upon the knuckle 13 so as to swing the 85 blades 18 and 19 within the body. The tool is then inserted in the casing, the wall thereof maintaining the finger 12 in its inner position, the blades being retracted within the body so that the tool may be lowered. 90 As soon as the tool passes out of the casing, spring 15 presses finger 12 outwardly, the tip of the finger pressing against the blade 18 and swinging the cutter into the position shown in Fig. 1. The underreamer is now 95 expanded and ready for work. To withdraw the underreamer, it is pulled upwardly, the knuckle 13 engaging the lower end of the casing or shoe and being forced inwardly as the body is drawn into the casing.

In Figs. 4 and 5, similar parts of a modified form of the tool are indicated by the same numbers as used for Figs. 1, 2, and 3, but with a prime added. The cutter 16' has arms 22 and 23 upon which are journalled 100 roller cutters 24 and 25. The action of the several parts in expanding and contracting 105 is the same as in the construction before de-

scribed. The recesses 9' and 10' must be cut to accommodate the passage of the cutter rollers.

What we claim is:

5. 1. An underreamer comprising a body, a cutter pivotally secured thereto, said cutter being provided with cutter arms which when in working position project beyond said body on opposite sides thereof and in 10 non-working position are disposed within said body, means on said body inwardly movable by engagement with a well casing, said means being connected to said cutter so that upon inward movement of said means 15 the cutter arms will be swung to innermost position.
2. An underreamer comprising a body, a cutter pivotally secured thereto, said cutter being provided with cutter arms which 20 when in working position project beyond said body on opposite sides thereof and in non-working position are disposed within said body, a finger pivotally mounted on said body and arranged to be moved inwardly by engagement with a well casing, said finger being connected with said cutter so that upon inward movement of said finger the cutter arms will be swung to innermost position thereby and upon outward 25 movement of said finger the cutter arms will be swung to projected position.
3. An underreamer comprising a body having a slot extending transversely therethrough, a cutter having diametrically opposite arms pivotally secured to said body and disposed in said slot so that said cutter may be turned to dispose said arms within said body or turned to dispose said arms so that they project laterally therefrom in 30 working position, and a finger mounted on said body and connected to said cutter so as to turn the latter, said finger tending to project beyond said body so as to maintain said cutter in projected position and when 35 said finger is in innermost position said cutter is within said body.
4. An underreamer comprising a body having a slot extending transversely therethrough, a cutter having diametrically opposite arms pivotally secured to said body and disposed in said recess so that said cutter may be turned to dispose said arms within said body or turned to dispose said arms so that they project laterally therefrom in 40 working position, a finger mounted on said body and connected to said cutter so as to

turn the latter, said finger and cutter being arranged such that said finger tends to project beyond said body when said cutter is in projected position and when said finger is 60 in innermost position said cutter is within said body, and means urging said cutter into working position.

5. An underreamer comprising a body having a slot extending transversely therethrough, a cutter provided with a cutter arm pivotally secured in said body and disposed in said slot so that said arm may be disposed in position such that the arm is within the body or may be disposed in a 70 position such that the arm projects laterally therefrom in working position, a finger pivotally secured to said body and disposed in said slot, said finger having an abutment faced outwardly, said cutter and 75 said finger being engaged so that when the abutment extends beyond said body the cutter extends beyond the body and when the abutment is disposed within said body, said cutter arm is retracted within said body, 80 and resilient means tending to urge the cutter arm outwardly.

6. An underreamer comprising a body having a recess extending transversely therethrough, a cutter provided with a cutter arm pivotally mounted in said body and disposed in said recess so that said arm may be disposed in a position such that the arm is within the body or may be disposed in position such that the arm is projected laterally therefrom in working position, a finger pivotally mounted in said body and disposed in said recess, the finger having an abutment facing outwardly, said cutter being provided with a notch, the tip of said 90 finger resting in said notch whereby to engage the cutter so that when the abutment is moved outwardly beyond the body the cutter is moved thereby beyond the body and when the abutment is moved within the 100 body the cutter arm is retracted thereby within said body, and resilient means tending to urge the cutter arm outwardly.

In witness that we claim the foregoing I have hereunto subscribed my name this 20th day of January, 1925.

JOHN GRANT.

In witness that we claim the foregoing I have hereunto subscribed my name this 16th day of January, 1925.

STEWART L. CAMPBELL.
